UNITED STATES PATENT OFFICE.

ELMER M. NELSON, OF ST. PAUL, MINNESOTA.

PORTABLE ROOFING HOLDER.

Application filed September 7, 1927. Serial No. 217,998.

My invention relates to a labor saving and safety device for building purposes, more particularly a portable roofing holder for holding a quantity of shingles in a position 5 on a roof or wall where it is readily accessible at all times for the carpenter or other person working on a building. The features and advantages of my device will be further set forth in the following specification, reference being had to the accompanying drawing, in which,

Fig. 1 is a perspective view of my device as set up for use on a sloping roof.

Fig. 2 is a vertical side or edge view of 15 my device in use on a vertical wall.

Fig. 3 is a side view of the device collapsed.

Referring to the drawing by reference numerals, my device comprises a main platform 20 or base preferably made entirely of metal strips of which 5 are a number of longitudinal parallel runners of bar stock all curved upwardly as at 5C at their front ends and the rear ends of the outer two bent downwardly each to form a prong of 5P. The front and rear end parts of said runner members are connected by cross bars 6 secured to said bars by suitable means such as rivets 7 preferably countersunk. 8 are 25 suitable angular braces secured as with rivets 9 to the runners to hold the base rigid. Both the braces 8 and crossbars 6 are preferably fixed on top of the runners the former extending rearwardly and fixed at horizontally registering points slightly rearward of the center of the base. 6X is a cross brace similar to braces 6 and located rearward of the rear ends of braces 8. 10 are bearing brackets fixed on brace 6X and their bearing 30 parts aligned to receive and retain a pivot rod 11 in parallel relation to and rearward of brace 6X, as clearly shown. On said pivot rod I mount a quadrangular bracket comprising a number of parallel flat metal 35 bars 12 each formed with a bearing 12B engaging the pivot rod 11. 13 are a pair of parallel brace bars connected to and bracing all of said bars 12, and 14 (see Fig. 1) are angular braces for further holding the entire 40 bracket rigid.

15 are L-shaped brackets fixed to the top side of the outer bars 5 and near their rear ends. The upright arm of each bracket 15 has one end of a brace bar 16 pivotally secured to it as at 17. Each said brace 16 is 45 thus adapted to swing in a plane vertically

over its base bar 5, the free end being bifurcated as at 16B to straddle a bolt 18 in the outer adjacent bar 12 of the pivoted bracket of my device and a thumb-screw 60 19 on the bolt secures the said brace 16, removably, to the pivoted bracket to hold the latter at right angles to the base. 20 are a number of apertures in the front or upper cross brace 6 of the base and through 65 which nails 21 may be driven into a wall 22 as in Fig. 2 to hang the entire device on the wall. In this use of my device a number of shingles, represented by the quadrangular dotted outline 23 in Fig. 2, are laid on the 70 pivoted bracket which is in a horizontal plane and such shingles are readily available to workmen putting shingles on a wall, the prongs 5P sticking into the wall and holding the device rigid.

75 The most useful application of my device is on the slope of a roof on which shingles are to be laid.

Fig. 1 shows the device with its base in an angular plane as on a roof and it will 80 be understood that the prongs 5P are driven lightly into the roof boards (not shown) to hold the device. Shingles in any suitable quantities are retained between said base and the bracket. When an area of roof has been 85 shingled close up to the device it can be readily moved up or down on the slope by simply raising the pronged end and skidding the device to the desired new position on the curved front end parts 5C of the base 90 members 5.

In Fig. 3 the device is shown collapsed, the bracket simply being disconnected from braces 16 and laid down on the base, and then said braces 16 laid down to resting 95 position. The device is thus in a very compact form and can be carried or shipped from one location to another.

I claim:

1. In a portable roofing holder a quadrangular base with parallel skid bars turned upwardly at their front ends and a number of said bars bent downwardly and pointed at their rear ends, a quadrangular frame pivotally mounted transversely on said base 100 and intermediate its ends, said frame adapted to be raised vertically with relation to the base and means for holding said frame in its upright position, said latter means comprising a number of brace bars each pivotally mounted with one end to the rear part 105 of the base and adapted to removably engage

the upper or free edge portion of said frame with its free end, and means securing each said brace to the frame.

2. The structure specified in claim 1 in which the free end of each brace is bifurcated, and said securing means comprises a rearwardly projecting bolt fixed in said frame, said bifurcated end adapted to straddle the

bolt, and a thumb-nut on said bolt for clamping the bifurcated part of the brace to the frame when the brace is in forwardly and upwardly inclined position and the pivoted frame is in a plane at right angles to the plane of the base.

In testimony whereof I affix my signature.

ELMER M. NELSON.
